United States Patent Office.

DAVID J. BARNETT, OF ALBION, INDIANA.

Letters Patent No. 80,115, dated July 21, 1868:

IMPROVED SAW-GUMMING DEVICE.

The Schedule referred to in these Letters Patent and making part of the same.

TO ALL WHOM IT MAY CONCERN:

Be it known that I, DAVID J. BARNETT, of Albion, in the county of Noble, and State of Indiana, have invented a new and useful Device for Gumming Saws; and I do hereby declare the following to be a clear and exact description thereof, sufficient to enable others skilled in the art to which my invention appertains to fully understand and use the same, reference being had to the accompanying drawings, which make part of this specification, and in which—

Figure 1 is a plan of my saw-gumming device.

Figures 2 and 3 are front and rear end views in line $z z$, fig. 1, the die and plates being set for gumming circular saws.

Figures 4 and 5 are similar views in the small line, fig. 1, the die and plates being set for gumming straight saws.

Like letters indicate like parts in the several figures.

My invention is an improved device for gumming straight or circular saws, and consists in providing a sliding die-post with removable dies, and operating said post by a cam, and also holding the saw between removable plates, whereby either a circular or straight saw may be readily and quickly gummed by merely changing the die and plates, as will be hereinafter more fully described.

In the drawings—

A represents the bed-plate, of suitable form and construction, and having at one end a bed, B, rising angularly therefrom.

To the inner end of this bed, B, I secure longitudinal pieces, $f g$, to which are connected transverse pieces or uprights, F G, which point inwardly, and allow a space to be between them.

A space is thus left between the pieces f and g , and between the pieces F G and the inner face of the rest, B. This space is adapted to receive die-plates H, which are constructed of flat pieces of suitable metal, and have openings of size and form corresponding to the dies E, which will be hereafter referred to.

The inner face of the bed is grooved vertically, and has its sides taper inwardly. The groove receives a plate, I, which is constructed similarly to die-plate H, only that its sides are bevelled, and form, with the groove, a dove-tail joint.

The pieces $f g$ receive screws $h i$, so as to bear against the plate H, and hold the saw to be gummed between it and the plate I.

C represents the slide, which encircles the bed-plate A, and has longitudinal motion to and from the bed, B.

On this slide I secure the die-block or head D, which is fitted to hold the dies E.

The inner face of the head D is perforated, as at c and d , to receive the stems or shanks of the dies E, which dies should be of form corresponding to that of the spaces between the teeth of either circular or long saws, as shown in figs. 2, 3, 4, and 5.

J is a cam, pivoted to the bed-plate A at the end opposite to the bed B, by means of a pin or journal, i. An opening is made in the periphery of this cam to receive a handle, K, whereby the cam may be readily operated, and thereby advance the slide C, and thus carry the die E towards the plate I through the space between the pieces F G.

The operation is as follows:

When a circular saw is to be gummed, the die-plates H I are placed into the space at the inner end of the rest B, and have the openings face downwards, as shown in fig. 3. The saw is introduced into this space between the plates, and secured in position by means of the screws $h i$. The die E is inserted into the lower opening, d , of the tie-head.

The cam J is now rotated, so that it will advance the slide C.

The die passes through the opening in plate H, and as it enters the opening in the plate I, it cuts away or gums the saw.

The motion of the cam being reversed, the slide C is free to be withdrawn. The saw may be shifted, and another cut be made, and the operation thus continued until the whole saw is gummed.

To gum long or straight saws, the position of the plates H I must be reversed, that is, their openings face upwards, as shown in fig. 5, and it is necessary that the openings in the plates should correspond with the peculiar die required, consequent to the shape of the teeth in long saws differing from those in circular saws.

The die is placed in the upper opening, *c*, of the die-block, and the saw being introduced, and retained in place by the screws *h i*, passing through the upper openings in the pieces F G, the cam J is rotated, the die advanced, and the saw is gummed the same as in the previous operation.

It will be seen that by means of different dies and die-plates, any kind of saws may be readily and quickly gummed.

Having thus described my invention, what I claim as new, and desire to secure by Letters Patent, is—

The saw-gumming device, consisting of bed-plate A, bed B, slide C, die-block D, removable dies E, removable slotted plates H I, screw-plates F G, and cam J, constructed, arranged, and operating substantially as represented and described.

The above specification of my device for gumming saws signed this eleventh day of December, 1867.

DAVID J. BARNETT.
